United States Patent Office

Des. 224,877
Patented Oct. 3, 1972

224,877

PICTURE FRAME

Daniel Fendrick, 4105 Leland St.,
Chevy Chase, Md. 20015

Filed June 29, 1970, Ser. No. 23,700

Term of patent 14 years

Int. Cl. D6—06

U.S. Cl. D6—242

FIG.1

FIG.2

FIG.3

FIG.4

FIG. 1 is a front perspective view of a picture frame showing my new design;

FIG. 2 is a side elevational view taken from the right of FIG. 1;

FIG. 3 is a top plan view thereof; and

FIG. 4 is a rear perspective view.

The drawing has been shaded for transparency.

I claim:

The ornamental design for a picture frame, as shown and described.
